UNITED STATES PATENT OFFICE

2,616,556

BLADE DISPENSING AND RECEIVING
PACKAGEJoseph Muros, Newtonville, Mass., assignor to The
Gillette Company, a corporation of Delaware

Application October 8, 1949, Serial No. 120,343

4 Claims. (Cl. 206—16)

1

This invention comprises a new and improved dispensing and receiving package for safety razor blades.

The principal objects of the invention are to provide a flat dispensing package of convenient size for the user or traveler that may be constructed and filled at low cost, which will safeguard the blades against damage to their cutting edges in transportation and storage and in which is incorporated a compartment for the safe disposal of used blades.

Going more into detail, the package of my invention includes in its structure a rectangular carrier strip in which a series of blades is anchored by having one end of each passed through the strip, and a cover strip marginally secured to the carrier strip thereby forming an intermediate blade-receiving compartment with a carrier strip and having an inlet slot opening into the said compartment. The cover strip is preferably extended to cover both sides of the carrier strip and the blades located thereon thereby serving two functions, i. e. forming one wall of the used blade compartment and forming also the cover of the package as a whole and protecting the unused blades therein. The carrier strip also serves two functions, i. e. it constitutes the other wall of the used blade compartment and at the same time locates and holds the unused blades in a convenient staggered relation so that a single blade may be easily grasped and removed by the user as required. The package of my invention is so advantageous from a standpoint of economy that it may be provided at no more than the cost of individual blade packaging and so may be discarded by the user when it has served its purpose.

It is believed that a continuous cover strip has not heretofore been used in this combination, that is to say, extended above both sides of an intermediate blade-carrying member, thus having the two distinct functions above described.

These and other features of the invention will be best understood and appreciated from the following description of a preferred embodiment thereof, selected for purposes of illustration and shown in the accompanying drawings, in which:

Fig. 1 is a view in perspective of the package on an enlarged scale;

Fig. 2 is a bottom plan view thereof;

Fig. 3 is a cross-section on the line 3—3 of Fig. 2;

Fig. 4 is a plan view of the open package;

Fig. 5 is a corresponding view in side elevation;

Fig. 6 is a plan view of an empty package show-

2

ing a portion of the carrier strip broken away; and

Fig. 7 is a view similar to Fig. 2 on a somewhat smaller scale showing part of the cover broken away and a used blade partially inserted in the used blade compartment.

The package may be formed of cardboard or other flexible sheet material. In its illustrated embodiment it comprises a body strip having a rectangular panel 10, folded to provide a short tongue 11 at one end and having a cover panel 12 at the other. To the panel 10 is secured an intermediate blade-carrying strip 13 having at one end a series of transverse slits 14 and being secured permanently in place by a staple 15 which passes through the tongue 11, the carrier strip and the panel 10 and is clenched with its ends on the latter.

The transverse slits 14 in the carrier are arranged in uniformly stepped relation and in each slit is removably secured one end of a blade 16. The blade herein shown is of well-known commercial type being sharpened on both edges and provided with a longitudinal median slot. It is shouldered at each corner and provided with elongated unsharpened end portions and it is these end portions which pass through the slits 14 in the carrier strip 13. The end shoulders of the blades abut against the surface of the carrier strip 13 as shown in Fig. 4 while the unsharpened end portions pass through the carrier strip as shown in Fig. 7.

The panel 10 is provided with a transverse blade-receiving slot 17 near the end of the panel 10 to which the cover panel 12 is attached or at the end which is remote from the inserted blade ends. In addition to attachment by the staple 15 and the panel 10 and the carrier strip are marginally secured together by an adhesive 18. Thus the unsecured areas of these two strips within the line of adhesive attachment constitute the opposite walls of a used blade compartment into which used blades may be inserted endwise through the slot 17.

It will be apparent that the panel 10, tongue 11 and cover panel 12 may be easily and cheaply formed by suitably bending a single rectangular strip of cardboard or the like. The carrier strip 13 may likewise be easily slotted and provided with a change of sharp blades. The panel 10 and the carrier strip are then united by adhesive and by the staple 15 as already explained and the package completed by tucking the cover panel 12 under the tongue 11. The complete package in this condition is shown in Fig. 1. When the

cover panel 12 is opened the blades, of which there are 5 in the illustrated package, fan out to some extent by reason of the resiliency of the carrier strip and extend in the position shown in Fig. 5 in which the uppermost blade in the series may always be conveniently grasped by the user and removed from the package. When the blade has served its purpose, the user may safely dispose of it by inserting it through the slot 17 into the used blade compartment and in this operation it will be noted that the advancing end of the used blade will move smoothly over the inserted ends of the sharp blades in the same general direction in which they extend and therefore without any obstructions from these blades or danger of catching thereon.

Having thus disclosed my invention and described in detail an illustrative embodiment thereof, I claim as new and desire to receive by Letters Patent:

1. A blade dispensing package having a compartment for used blades, comprising an elongated carrier of sheet material, a plurality of thin flexible blades removably attached to the carrier adjacent to the blade ends, and a cover of continuous strip material enclosing the blades on one side of said carrier and being extended about the back of the carrier, adhesively attached to the marginal edges of said carrier back about an area providing therewith a used blade compartment and having a transverse slot adjacent to one end of said area.

2. A dispensing and receiving package for safety razor blades comprising an elongated carrier card having a series of transverse slits therein, a plurality of thin flexible blades each projecting obliquely at one end through a slit of the card, and a flexible strip of sheet material covering the inserted blade ends, marginally secured to and cooperating with the card to provide a blade-receiving compartment and provided with a transverse blade-receiving slot adjacent to that end from which an inserted used blade will pass freely over the said blade ends.

2. A dispensing and receiving magazine for

safety razor blades comprising a rectangular carrier strip provided adjacent to one end with a plurality of transverse slits, a thin flexible unused razor blade frictionally held at one end in each of said slits and projecting at an acute angle through the carrier strip, and a second strip underlying the carrier strip and marginally secured thereto thus providing an enclosed used blade compartment, said second strip being provided with a transverse slot remote from the slotted end of the carrier strip for the introduction of used blades.

4. A dispensing and receiving magazine for razor blades, comprising a rectangular carrier strip having a series of parallel transverse slits, a corresponding series of unused blades each of which passes at one end through a slit of the carrier strip with its end projecting through the strip at an inclination and directed toward one end of the strip, and a cover strip marginally secured to the back of the carrier strip and cooperating therewith to form a blade-receiving compartment therebetween, the cover strip having a blade inlet slot opening into said compartment near that end of the strip away from which the projecting blade ends are directed, whereby an inserted used blade will pass smoothly over the projecting ends of the unused blades in the magazine.
